CLAIM

The ornamental design for a cup shelf for dish rack, as shown and described.

DESCRIPTION

FIG. 1 is a top perspective view of a cup shelf for dish rack showing our new design in condition of use.

FIG. 2 is a top perspective view of a cup shelf for dishrack.

FIG. 3 is a bottom view thereof.

FIG. 4 is a front view thereof.

FIG. 5 is a rear view thereof; and,

(Continued)

FIG. 6 is a right side view thereof, with the left-side view being a mirror image.

The broken lines depict portions of the cup shelf for dishrack that form no part of the claimed designed. The broken lines showing of the dishrack in FIG. 1 are for the purpose of illustrating environmental structures and form no part of the claimed design.

1 Claim, 6 Drawing Sheets
